CLAIM

I claim the ornamental design for a barbecue grill having a football goalpost motif, as shown.

DESCRIPTION

FIG. 1 is a front elevation view of a barbecue grill having a football goalpost motif showing my new design;

FIG. 2 is a top plan view thereof;

FIG. 3 is a right side elevation view thereof;

FIG. 4 is a back elevation view thereof;

FIG. 5 is a bottom plan view thereof;

FIG. 6 is a left side elevation view thereof; and,

FIG. 7 is a perspective view thereof.
